UNITED STATES PATENT OFFICE.

HAROLD W. SHONNARD, OF MONTCLAIR, NEW JERSEY, ASSIGNOR TO ELEVATOR SUPPLIES COMPANY, INC., A CORPORATION OF NEW JERSEY.

DOOR HANGER.

Application filed July 29, 1926. Serial No. 125,656.

The present invention relates to an improved form of hanging support for doors and gates of the type that are moved back and forth in their planes; and more particularly for elevator doors.

The tendency in modern office buildings and the like is to provide elevator shafts with wider door openings and heavier doors, and one of the objects of this invention is to provide a form of rolling hanger which will give a maximum of strength within the restricted space conveniently available for these hangers under the conditions of standard elevator construction.

Another object of this invention is to provide a hanger for the purpose stated so constructed as to make it easy for an ordinary workman to adjust the parts to compensate for the wear and tear incident to use.

A further object is to provide a novel construction of the rolling parts and the associated track or rail, which prevents undue friction between such parts and the rail, even in cases where the doors and rolling parts are not in perfect vertical alignment.

Further objects and advantages of this invention will fully appear in the following description.

Certain preferred forms of this invention are illustrated in the accompanying drawings, wherein Figure 1 is a view in front elevation of one form of my improved hanger, Figure 2 is a vertical sectional view through the middle of the same, Figure 3 is a sectional view of a detail, taken on the line 3—3 of Figure 2, Figure 4 is a view in rear elevation of a modification, and Figure 5 is an end view of the same.

The hanger shown in Figures 1 to 3 comprises a stiff box, which may be made either of cast or of bent metal. This box is closed at the top 10, bottom 11 and front 12. In back it is partly closed near the top as shown at 13, and the sides 14, 15 are cut away as clearly shown in Figure 2, to admit the rail or support 16 from which the hanger is suspended. To impart added stiffness it is preferred to give the back a dished shape as shown in Figures 1 and 2.

A bearing bolt 17, with a polygonal head 18 is inserted through the upper part of the dished portion of the front, and its end is screwed into the rear 13 of the box.

A bushing 19 is fitted over the shaft or bolt 17, and the ground roller 20 turns on roller

bearings 21 supported on said bushing. The roller 20 runs upon the upper surface of the rail 16 and against the under surface there runs a guard roller 22, carried in a groove on the stub shaft 23.

The shaft 23 passes through an inclined slot 24 in the lower part of the dished portion of the back of the box, and, as clearly shown in Figure 3, this shaft is cut on opposite sides to fit the straight sides of said slot 24, whereby the shaft is prevented from turning. The outer or front end of this shaft is threaded, and carries a nut 25 over a washer 26, by means of which the shaft is tightly secured in place. As shown in Figures 1 and 3, it is preferred to provide the washer 26 and the surface against which it bears with striations or ridges, adapted to fit together.

The construction just described makes it possible to adjust the parts from time to time as made necessary when the parts begin to wobble or rattle due to wear. To accomplish this, the nut 25 is loosened, and the washer 26 is moved back far enough to free the interlocking ridges. The shaft 23 is then moved upward, or to the right in Figure 1, far enough to bring the roller 22 firmly up against the rail 16, and then the washer is pressed back again against the front of the box by screwing down the nut 25.

The door is fastened to the bottom of the hanger box by the bolts 27, passing through openings 28 in the bottom 11 of the box, and fitting openings in the bent plate 29, which is slipped over the rear edge of the bottom 11. The head of each bolt 27 rests on the top of the bent plate 29, while the nut 30 is screwed up tightly against the under side of said plate, as shown in Figure 2. The nut 31 secures the top of the door (not shown).

The final assembling of the rail hangers and door must, of course, be accomplished in the building where they are to be used, and it is found in practice that the workmen employed in such buildings cannot always be trusted to assemble the parts with accuracy. Among the troubles to be contended with in this regard is the fact that the bolts 27 are not always inserted in the exact vertical position. In such cases there is a tendency for the rollers to jam on the rail, causing undue friction in operation.

To avoid this, in my preferred construction, the upper surface of the rail 16 is made in the arc of a circle in cross section; and,

as shown by dotted lines in Figure 2, the lower surface of the rail conforms in cross section to a circle struck by a longer radius than that of the top surface but from the 5 same center.

The result of this construction is that jamming is avoided in those cases in which the bolts 27 are not inserted accurately in a vertical position in the top of the door.

10 In Figures 4 and 5 is shown a modification of the invention especially adapted to extra heavy doors. Here the back, front and top and bottom of the box are formed by bending a metal plate 32 of any desired length.

15 This plate is dished at as many points as may be required, as shown at 33 and 34 in Figure 4, and each dished portion has an inclined slot 24 cut in it, with serrations on the adjacent surfaces as indicated by dotted lines 20 in that figure. These slots, of course, accommodate the flattened stub shafts 23 of hangers such as have already been described with reference to Figures 1, 2 and 3.

The ends of the elongated box are formed 25 of bent or cast metal as shown in Figure 5, and in dotted lines in Figure 4, at 35. If de-

sired bent stiffening members may be used at intervals, as shown in dotted lines at 36 in Figure 4. The bolts for fastening the doors may be slipped in from the back through the 20 openings 37.

Various changes may be made in the structures shown without departing from the scope of my invention, and I do not limit myself to the details herein shown and described.

What I claim is—

A guiding and supporting rail in the form of a substantially oblong solid bar extending across the entire length of the door's path of movement, said bar having its top and bottom surfaces shaped transversely on circular arcs struck with different radii from a common center near the upper surface of the bar, and a door hanger provided with a supporting 40 sheave resting on the upper surface of said rail, and a guide member engageable with the under surface thereof.

In testimony whereof I have hereto affixed my signature on this 16th day of June, 1926.

HAROLD W. SHONNARD.
